RESILIENT MOPHEAD STRUCTURE AND
HANDLE MOUNTINGFranz Wagner, Chicago, Ill., assignor to O-Cedar
Corp'n, Chicago, Ill., a corporation of Illinois

Application January 21, 1948, Serial No. 3,495

10 Claims. (Cl. 15—147)

1

This invention relates to a mop structure. The invention is particularly useful in connection with a dust mop, and similar mops. In the handling of mops, such as, for example, a dust mop, it is difficult to keep the mophead properly positioned upon the floor, with the nose or forward portion of the mop tightly engaging the floor so that it may be directed readily into corners and places difficult of access. If spring means are employed in conjunction with the handle for exerting pressure against the top of the mop, the resulting structure allows lateral play and the mophead is difficult to control because of such lateral play.

An object of the present invention is to provide a mophead structure in which a resilient body is employed to integrate the parts of the head into a firm and easily controlled body, while at the same time providing a resilient connection between the handle and the head for effecting accurate control thereof. Yet, another object is to provide a mophead and handle connection therefor in which a resilient member joins the head to the handle, the resilient member, however, laterally engaging the walls of the head so as to permit no lateral play and to retain accurate and firm control of the mophead. Yet, another object is to provide a mophead structure with a resilient connection between the head and handle, and means controlling the sweep of the handle with relatively high flexibility, and then sharply reducing such flexibility after a predetermined limit of sweep is reached. A still further object is to provide a resilient integrator device employed as a central portion of a mophead for uniting the parts of the head firmly and rigidly in the central structure, while providing a flexible connection between the central structure and a mop handle. A still further object is to provide a resilient mophead structure in which mop-holding prongs are embedded, the prongs extending at a spaced relation from the mophead, and the head being provided with a handle-receiving socket resiliently connected to the structure in which such prongs are embedded. Other specific objects and advantages will appear as the specification proceeds.

The invention is illustrated, in a single embodiment, by the accompanying drawings, in which—

Figure 1 is a perspective view of a mop structure embodying my invention; Fig. 2, a top plan view of the structure on a reduced scale; Fig. 3, an enlarged transverse sectional view, the section being taken as indicated at line 3—3 of Fig. 2; Fig. 4, a longitudinal sectional view, the section being taken as indicated at line 4—4 of Fig. 2;

Fig. 5, a broken detail sectional view showing the handle socket in raised position; Fig. 6, a broken bottom plan view; Fig. 7, a plan view of a modified form of mop structure embodying my invention; Fig. 8, a plan view of the metal-retaining member employed in the structure shown in Fig. 7; and Fig. 9, a transverse sectional view, the section being taken as indicated at line 9—9 of Fig. 7.

In the illustration given, 10 designates a central resilient body formed of rubber, or any other suitable resilient material. The body 10 has the general shape of a shield, and is provided along its sides and front portion with a recess 11 adapted to receive a plate 12. The plate 12 has an inner downwardly-flanged end, which is tightly received within the recess 11 of the resilient block 10. The block 10 has also embedded therein metal prongs 13, which extend outwardly around the plate 12 a spaced distance and terminate near the forward end of the plate in slightly spaced-apart relation. Upon the free ends 14 of the prongs are drawn the sleeve member 15 to which strands 16, forming the mop body, are secured. The outer end of the plate 12 is preferably turned downwardly and outwardly at 17 so as to provide a support for the inner surface of the tapered sleeve 15.

The resilient body 10 is slotted from its rear side inwardly a substantial distance at spaced points and along the lines 18, as indicated best in Fig. 3. The slitting of the rubber body provides between the spaced slits a resilient neck 19 with which is integrally formed a handle socket 20. With the structure shown, it will be noted that the tops of the sides 21 of the neck member 19 engage the inner sides of the body 10 so that lateral movement of the flexible neck 19 is restricted, thus giving effective control of the lateral movements of the mophead.

The socket portion 20 is provided with an opening 22 adapted to receive a mop handle. The opening 22 may be circular in shape or, if desired, elliptic in shape, depending upon the type of handle which is to be employed.

The neck 19, as illustrated more clearly in Figs. 4 and 5, is provided with a plurality of transverse slots 23. Such slots permit rapid flexing of the neck 19 up to a limited point, as illustrated more clearly in Fig. 5. The handle is raised easily to the point illustrated in Fig. 5, and at that point, where the top edges of the material meet each other, thus bridging the tops of the slots, further upward movement is less easy. Thus, after the handle 24 has been raised to the position indicated in Fig. 5, further raising of the handle will

impose much greater pressure upon the forward portion of the mophead. It will be understood that such slots may be of any desired number and location, and the shape of the slots may be varied depending upon the material used and the desired pressure which it is desired to place upon the nose or forward portion of the mop.

Operation

In the operation of the mop, the mop handle 10 is placed within the socket 22, which is preferably slightly smaller than the handle so that the handle is tightly held within the socket. The handle is then raised, the slots 23 permitting an easy movement up to the point at which the mopping operation is conveniently carried on. At this point, the upper slots are bridged over, as illustrated in Fig. 5, and further elevation of the mop places greater pressure upon the mophead. The mophead may be moved back and forth while the neck flexes readily. The relatively wide neck 19, which engages the adjacent walls of the resilient member 10, enables the mophead to be guided laterally without play between the parts, while at the same time permitting easy flexing in the connection between the handle socket and the resilient body. When released, the resilience of the neck 19 brings the handle 24 into horizontal alignment with the body 10, and the mop may be stored in this position. Even if the mop should be stored in a closet resting upon the nose of the head, the resilience of the neck 19 maintains the handle 24 in alignment with the head.

The resilient body 10 forms a firm integrating structure by which the mophead parts are united, while at the same time permitting the slight yielding of such parts under blows, collisions, etc. The result is that the structure is cushioned by its center against violent blows against objects engaged by the mophead so that, by reason of such resilience and the padded sleeve 15 of the mop, no damage or injury is done to such objects. At the same time, the operator has complete control of the mophead and is able to move it accurately into difficult corners, the resilient neck 19 holding the nose of the mop downwardly against the floor as it enters such corners, etc.

In forming the central resilient body 10, the prongs 13 may be placed in position within the mold and the molded body cast in the form illustrated. In the resulting structure, the prongs 13 provide a rigid frame extending along the walls 18 of the recess and causing the flexing joint between the handle socket and the body 10 to occur in the forward portion of the body 10, thus directing pressure exerted by the raising of the handle against the forward portion of the mophead. The positioning of the prongs 13 along the recess further maintains such walls in true alignment and facilitates the easy swinging of the neck 19 between such rubber-covered prongs.

The plate 12 is preferably formed of metal, plastic, or other suitable rigid material, and the inner edge of the plate provides a frame which locks the edge portions of the resilient body against flexing whereby the flexing of the structure is concentrated within the forward portion of body 10 where it is most effective for the purposes above described.

In the modification illustrated in Fig. 7, the mop body 25 is formed in its entirety of rubber or other resilient mold material and is equipped with a single piece metal-retaining member 26 embedded in the body 25. A fabric sheath 27 is received about the retaining member 26. If de-

sired, the outer edge of the rubber body 25 may be equipped with vertical ribs or with longitudinal ribs for the better gripping of the fabric sheath 27 and to prevent the fabric sheath from working off of the retaining member 26 when the mop is shaken or otherwise used.

The mop socket 28 is connected by a flexing neck and shaking device 29 integrally with the body 25.

The socket and body provide a non-scratch buffer or protector which prevents injury to furniture when the mop is brought into contact therewith.

In all of the modifications, the flexing neck serves the very important function of keeping the toe of the mop downwardly against the floor and thus insuring the contact of the mop with the floor when the same is projected into corners and other difficult places.

While in the foregoing specification, I have set forth a specific structure in great detail for the purpose of illustrating an embodiment of the invention, it will be understood that such details of structure may be varied widely by those skilled in the art without departing from the spirit of my invention.

I claim:

1. In a mop structure, a central resilient flexible body to serve as a shock absorber, prongs fixed in said body and extending laterally and forwardly thereof, a fabric body supported upon said prongs, said resilient body having a central recess extending rearwardly and an integral neck portion in the recess and extending in the plane of said body and equipped with an integral socket providing with said body a non-scratch buffer, and a handle received within said socket, said neck arcuately flexing when said handle is raised or lowered.

2. The structure of claim 1 in which said neck is provided with slots to facilitate said flexing.

3. The structure of claim 1 in which said neck is provided with slots which extend transversely of said neck.

4. In a mop structure, a central pliable elastic body equipped with a peripheral recess, a plate extending about a portion of said body and having an edge received within and tightly held by the walls of said recess, prongs embedded within said elastic body and extending outwardly and forwardly toward the front of said plate, a fabric sheath received upon said prongs, said elastic body being slotted at spaced points from its rear inwardly to provide an arcuately flexing neck equipped with a socket, and a mop handle engaging said socket.

5. In a structure of the character set forth, a central rubber body having its side walls inclined forwardly and inwardly and provided with a peripheral recess, a plate having a recess therein which enlarges rearwardly and outwardly and is adapted to be received snugly within said peripheral recess of the rubber body, said rubber body having at its rear a recess and a resilient flexible neck in said recess and integrally joining the forward portion of said rubber body, means for securing a handle to said neck, and a pair of prongs having portions extending parallel with and adjacent said recess in the rear portion of said molded body and then extending outwardly and forwardly of said plate.

6. In a structure of the character set forth, a thick rubber body having a recess extending rearwardly and a thick integral neck received within said recess and integrally formed at its

forward end with said body, said neck near its point of junction with said body being provided with a plurality of spaced transverse slots whereby said neck may be flexed upwardly and downwardly, the side walls of said neck during said flexing engaging the side walls of the recessed body, and a pair of prongs embedded within said rubber body and running parallel with and adjacent said recess in the body, said prongs being extended outwardly and forwardly of said body for receiving a fabric mop structure.

7. In a structure of the character set forth, a resilient flexible body having a recess extending rearwardly and a resilient flexible neck in said recess and integrally joining the forward portion of said body so that said neck may be flexed upwardly and downwardly, said neck normally lying in the plane of said body when unflexed and the side walls of said neck during said flexing engaging the side walls of the recessed body whereby lateral flexing of said neck is restrained, and retaining means embedded within said body and running parallel with and adjacent said recess in the body and having prong means extending outwardly and forwardly of said body for receiving a fabric mop structure.

8. The structure of claim 7 in which said neck is provided with slots which extend transversely across the upper and lower surfaces of said neck to facilitate said flexing.

9. In a mop structure, a resilient flexible body having a recess extending rearwardly and a resilient flexible neck in said recess and integrally joining the forward portion of said body so that said neck can be arcuately flexed upwardly and downwardly, said neck normally lying in the

plane of said body when in unflexed condition and the side walls of said neck during said flexing engaging the side walls of the recessed body whereby lateral flexing of said neck is restrained, and means for supporting a fabric mop structure about said body.

10. The structure of claim 9 in which said neck is provided with slots which extend transversely across the upper and lower surfaces of said neck to facilitate said flexing.

FRANZ WAGNER.
